UNITED STATES PATENT OFFICE

128,003

DESIGN FOR A SIGHT OPENING PLATE FOR CARPET SWEEPERS

Carl C. Parrish, Shelbyville, Ind., assignor to Porter-Steel Specialties, Shelbyville, Ind., a co-partnership composed of George M. Parker, Parrish Fuller, and Hester P. Fuller.

Application January 25, 1941, Serial No. 98,382

Term of patent 7 years

To all whom it may concern:

Be it known that I, Carl C. Parrish, a citizen of the United States, residing at Shelbyville,
in the county of Shelby and State of Indiana,
have invented a new, original, and ornamental
Design for Sight Opening Plate for Carpet
Sweepers, of which the following is a specification, reference being had to the accompanying drawing, forming part thereof.

Fig. 1 is a plan view of a sight opening for a carpet sweeper, showing my new design; and

Fig. 2 is a section of the plate on line 2—2 of Fig. 1.

I claim:

The ornamental design for a sight opening plate for a carpet sweeper, as shown.

CARL C. PARRISH.
